UNITED STATES PATENT OFFICE.

DAVID R. RICHARDS, OF ST. LOUIS, MISSOURI.

WINDOW CONSTRUCTION.

Application filed October 8, 1920. Serial No. 415,522.

To all whom it may concern:

Be it known that I, DAVID R. RICHARDS, a citizen of the United States, residing at St. Louis, in the county of St. Louis and 5 State of Missouri, have invented certain new and useful Improvements in Window Constructions, of which the following is a specification.

My invention relates to improvements in 10 window construction, one object being the production of a structure which will permit of instant and ready removal of either or both sashes from the casing for the purpose of painting, cleaning, repair or in 15 fact for any reason where it is desirable to have ready access to one or both sashes.

Another object of my invention is the provision of a window construction which will permit either or both sashes being 20 brought inwardly away from the frame to enable all surfaces of such sashes to be operated upon for any purpose, and which will provide for suspending and sustaining the sashes in the most desirable and advan- 25 tageous position for the desired purpose.

Another object of my invention is the provision of a window construction which will be of attractive and ornamental exterior appearance while possessing all of the 30 advantages above stated and which will be capable of production and installation at about the same price as window constructions in common and general use, thus commanding the structure as highly desirable, 35 efficient and practical.

With the attainment of the objects stated in view, my invention consists of a window construction embodying novel details of parts and arrangement of the elements comprising the structure, substantially as 40 shown, described and particularly defined by the claims.

In order that the construction in detail and the advantages which accrue from my 45 structure may be understood, I have shown in the accompanying drawings a window structure embodying the principles of my invention, believed to be the best construction for the carrying out of my invention, 50 and in which:

Figure 1 represents a front elevation of a window construction embodying my invention, with both sashes fitted in position and shown in closed position.

Fig. 2 is a sectional view taken on the 55 line 2—2 of Fig. 1.

Fig. 3 is a sectional view taken on the line 3—3 of Fig. 2.

Fig. 4 is a vertical sectional view through the upper part of the window frame and 60 showing the hinged parts swung out of their normal positions.

Fig. 5 is a detail view of a portion of one of the sashes, showing particularly the pintle for suspending the sash when being 65 cleaned or for other purposes.

Fig. 6 is a perspective view showing the manner of removing and supporting the upper and lower sashes, and

Fig. 7 is a horizontal sectional view of 70 the complete window frame.

Referring by numeral to the figures, in which the same numbers of reference are used to designate similar parts in all the views, the numeral 1 designates the casing 75 or frame of the window as a whole which is provided with the usual base portion 2, and the side casings 3, which enclose and form the compartments for the weights, whose cords 4, are guided over the grooved 80 pulleys 5, and which cords are connected to the sashes in any desired manner.

This construction provides a frame or casing of the same general appearance as of windows in common use, the guideways 85 for the sashes being noted at 6 and 7, guideway 6 being formed by the outer continuous vertical strip 8, and the intermediate strip 9, having the hinged portion 10, connected to a stationary upper portion by the 90 hinge 11, while the inner guideway 7 is formed by the upper and lower short rigid strips 12, and the intermediate strip 13, such intermediate strip being hinged at 14 to permit such strip to be moved or swung 95 outward, as clearly shown in Fig. 4, and which when in closed position, as shown most clearly in Fig. 2, completes the guideway 7 and such hinged strip 13 is secured in stationary position by means of the upper 100 and lower pivoted catches or buttons 15.

In the guideways 6 and 7 are mounted the upper and lower sashes 16 and 17, which when the parts are in normal position, as shown in Figs. 1 and 2, are permitted the 105 usual vertical movement in the casing, and when necessary to have access to the lower sash, it is simply necessary to throw the

hinged strip 13 outward, after the release of catches 15 to the position shown in Fig. 4, when said lower sash may be lifted clear from the casing to the extent allowed by 5 the sash cord, and in this position cleaned, painted, repaired, or operated upon in any manner desired, and if necessary such sash may be hung on the loops 18 at the side of the casing by means of the pintles 19, 10 seen in Fig. 5, to suspend the sashes and permit easy access thereto. Also, as seen in Fig. 4, access is obtained to the upper sash by moving the hinged portion 10 of the intermediate hinged strip 9 outwardly, as 15 shown in Fig. 4, and supporting such strip upon the removable bracket 20, which allows a clearance and permits such upper sash to be drawn inwardly and if desired suspended by means of the pintles 19 and 20 loops 18.

To allow sufficient space in which to manipulate the sashes, the lower inner faces of the frame are recessed and the ends of the loops 18 are also secured therein and assured 25 greater rigidity.

From the foregoing description, taken in connection with the drawings, it will be apparent that I provide a window construction which will be of attractive exterior 30 and which will permit of instant removal of either sash from the window casing for the purpose of cleaning, painting or repair, without interfering with the sash cords which allow such movement or play of the 35 sashes, and which improvements will thus render very easy access to the sashes for

any desired purpose and which improvements will not add materially to the cost of the structure.

I claim:

1. The herein described improvement in window construction, consisting of the frame proper, outer sash guide-strips secured to the frame, parting strips each composed of an upper vertical section, a lower section, and an intermediate section, said intermediate section being hinged at its upper end to the lower end of said upper section to swing inwardly in a vertical plane, and inner guides each consisting of upper and lower rigid sections, and an intermediate section, said intermediate sections being hinged at their inner edges to the frame to swing inwardly, and pivoted catches mounted on said upper and lower sections for securing the hinged sections in normal position. 40 45 50 55

2. In a window construction, the combination with the frame proper and the upper and lower sashes, of an outer continuous 60 guide strip, a parting strip composed of upper and lower rigid sections and an intermediate hinged inwardly and vertically swinging section, an inner guide strip composed of upper and lower rigid sections 65 and an intermediate hinged inwardly swinging section, latches for securing the intermediate section in rigid position, a series of loops secured to the frame and pintles carried by the upper sash to engage said loops. 70

In testimony whereof I affix my signature.
DAVID R. RICHARDS.
